SKILL GAME

William Turrall, Wimbledon, London, England

Application October 29, 1938, Serial No. 237,592
In Great Britain November 9, 1937

13 Claims. (Cl. 273—95)

This invention relates to an improved coin freed apparatus for playing a game of skill and relates to a ball game apparatus simulating the well-known bowling game or a game of bowls or skittles.

The usual arrangement in this type of game is that in return for a coin or token of predetermined value a set number of balls are delivered which once used by the player are retained by the apparatus whether a prize winning score is attained or not. The consequence is that in an amusement centre, unless a player is really determined to win a particular prize two or three consecutive losses are apt to discourage the player and he will abandon that particular game entirely for something more attractive.

The object of the present invention is to provide an apparatus in which in return for a coin or token of predetermined value a number of 20 balls are delivered for bowling but which are continually returned to the player for re-use until the player has succeeded in reaching one of a number of prize winning scores or has made a predetermined number of losing shots.

According to this invention an apparatus for the purpose set forth comprises a plurality of targets adapted to be displaced individually by missiles and when displaced to close circuits of electrically operated score indicating means, said 25 score indicating means comprising a number of indicators, and the targets being arranged in corresponding sets, means being provided to operate automatically a "game-ended" notifying device when indicator reaches a predetermined or maximum score indication.

In carrying one form of the invention into practice the apparatus comprises a coin freed mechanism which in return for the insertion of a coin or token of predetermined value effects the release of a number of balls to the lower end of an inclined table the upper end of which is provided with a ramp whereby the balls when bowled up the table are deflected against movable targets or objects, movement of a target when struck causing the closure of an electric circuit to one of a number of electromagnetically operated switches which in turn closes an indicator-lamp circuit. Each said switch is a step-by-step device which brings into circuit an additional indicator lamp each time a target of particular value or colour is struck and at the end of its movement the switch operates a make and break switch in the main circuit to render the game inoperable until a further coin is inserted in the 55 coin freed mechanism.

The used balls are returned continuously to the player for replay until any one of the step-by-step switches has completed its full movement, that is, until a player has scored a full complement of any one of a number of prize winning or losing ranges which are indicated by the lit indicator lamps. When this has been effected the return movement of any further balls is prevented by a spring loaded arm or shaped plate or gate adapted to be projected across the return chute, 10 said arm plate or gate being retracted by the ball in play when it passes over a plate to operate a switch which controls an electric-magnetic device to release another ball to the player.

Suitable counter devices may be provided to 15 indicate the number of complete scores effected and the number of games played to maintain a check upon the issue of the prizes and the money taken.

Insertion of a further coin after a completed 20 game can effect the release and return of the step-by-step switches to zero positions. An audible signalling device may be included in the indicator-lamp circuits to indicate the completion of a range or score.

In order that this invention may be clearly understood and readily carried into effect sheets of drawings are appended hereto illustrating an embodiment thereof and wherein—

Fig. 1 is a sectional side elevation view of 30 the apparatus with the electrical operating means and circuit omitted.

Fig. 2 is a plan view of Fig. 1.

Fig. 3 is a front end elevation view of the machine.

Fig. 4 is a detail sectional elevation of one of the targets.

Fig. 5 is a detail elevation view of one of the switch devices operated from a target for closing circuits to illuminate lamps indicating a score and also for breaking a circuit of a device for preventing further play when a predetermined number of lamp circuits have been closed.

Fig. 6 is a detail sectional elevation view of the illuminated score indicating device, and

Fig. 7 is a diagrammatic view of the complete circuit.

Referring to the drawings the body part of the apparatus comprises the arrangement shown in Figs. 1, 2 and 3 in which an inclined panel 1 affords by its upper surface, the surface along which each ball is projected with the object of striking one of a number of movable targets 2 arranged in staggered or other suitable formation upon a target panel 3. The targets are pref-

erably arranged to afford a triangular assembly as shown in Figs. 2 and 3, and each target preferably comprises a triangular plate to facilitate the triangular assembly, each plate being, as shown in Fig. 4, a fairly thick member 4 with a central aperture 5 in which is sunk a faceted or other suitable glass 6 which during the game is permanently illuminated by a lamp 7 with a reflector 8, the number of lamps 7, each with its reflector, being supplied only to evenly illuminate the rear of the targets and the prismatic members. The glass 6 may be mounted in the board 3.

Each target member 4 is supported by a pair, or more (preferably three), of legs 9 slidably guided through apertures in the target panel 3, such legs resting upon the upper fingers of spring contact switches 10 adapted, when the target is depressed against the influence of springs 12 around the legs 9, when a ball strikes the appropriate target, to close a circuit of one of a number of devices, hereinafter described for operating illuminated score indicating means.

In practice two balls are sufficient, and one is indicated by broken lines at 13 in Fig. 1 ready for throwing up the inclined playing surface, and the other is indicated by broken lines at 14 returning after play down an inclined runway 15 spaced beneath the playing panel 1 and conveniently forming the base of the game apparatus by being supported on transverse struts 16 secured across side walls 17 which extend the full length of the apparatus and are increased in depth at their rear ends to afford lateral panels 18 which support side nets 19 to prevent the balls from being deflected out of the apparatus.

The rear end of the apparatus is constituted by a rectangular box like structure 20 open for the major portion of its front side to receive the rear upper end of the target panel 3, the lower front end of which abuts against a transverse board 21 supported across the side wall parts 18 so that it can pivot on an axis transverse in relation to the longitudinal direction of the game apparatus, this pivoted board normally occupying the position shown in full lines, but adapted when a ball falls upon its exposed front part to be deflected downwards by the weight of the ball to deliver the ball to the ball return runway 15. In rearward prolongation of the runway 15 is an inclined cover panel 21a spaced beneath the target panel 3, but pivoted downwards to the position shown in broken lines in Fig. 1 to afford ease of access to the contacts and other elements carried beneath the target panel 3. The panel 21a carries the lamps and reflectors 7 and 8 respectively.

The balls are deflected upwardly at the rear end of the inclined panel 1 by a steeply inclined or arcuately shaped ramp 22, so that if sufficient impetus is applied to the balls they will ascend sharply as they leave the panel 1 and fall upon one of the targets or other part of the target panel 3 resulting in the appropriate target being momentarily urged downwardly against the influence of its springs 12 to close the appropriate contact or contacts 10.

The targets 2 are given predetermined values, and by distinctively colouring their glasses 6 a player can endeavour to achieve a high score by appropriate selection of target members to be aimed at when delivering a ball along the playing surface. In the particular arrangement shown simply by way of example there are four groups of targets, viz., coloured red, green, amber and blue, of which red has the higher value and is

allocated say two target pieces. Green is next in value and has say four targets, amber being the next with say six targets, and blue being the losing element has say ten or twelve targets. The various coloured targets are scattered over the panel 3 so that it requires some considerable skill to direct a ball successfully against any particular target, it being understood that the prizes awarded decrease in value dependent upon the colour value of the score attained, viz., red, green, 10 and amber.

Each target group has associated therewith a score indicator in the form of a set of illuminated glasses or other transparencies corresponding in colour to the appropriate target group, and as shown in Fig. 3, three sets of illuminated indicators, each with its illuminated glasses 23 arranged in triangular formation, are disposed on a front upper panel 24 of the box like rear part 20, the three sets being indicated by the reference letters R, G and A to indicate red, green and amber coloured lights respectively, whilst the blue score indicating lights are arranged as a line of illuminated glasses B. The arrangement is such that each time a target is struck by a ball a correspondingly coloured indicator glass 23 is illuminated, and the intention of the game is to continue play until a complete set of coloured lights is illuminated whereupon return of the balls to the player is automatically prevented and an audible or visual warning is given. This score indicating means and other associated parts are operated electrically and Fig. 7 shows the complete circuit, but only one of each of the targets being shown to obviate a complicated diagram, and also only one of the sets of score indicators and circuit closing device appropriate thereto being shown as the operating means is the same throughout.

Referring more particularly to Fig. 7 the targets are indicated by the references B⁴, G⁴, R⁴ and A⁴ blue, green, red and amber respectively and the lamps 7 which during the game permanently illuminate the targets are connected to a low voltage (e. g., six volts) source of current L. V. by leads 1a and 1b, and the contacts 10 of each target are connected by leads 10a to electromagnets B¹, G¹, R¹ and A¹ and by leads 10b to one pole of a high voltage (e. g., twenty volts) source of current H. V., the electromagnets being connected in turn to the other pole of the H. V. source of current by a lead 10c through suitable contacts. The armature 25 of each electromagnet is connected to one end of a pivoted arm 26 carrying a pawl 27 engaging a ratchet wheel 28 which is lightly spring loaded by a spring 29 to yieldingly oppose the thrust of the pawl 27 when the armature is moved consequent upon momentary energising of the armature when a target is struck by a ball. A locking pawl lever 30 with each ratchet wheel prevents reassertion of the spring 29 until a game is completed, and a suitable coin operating contact 34 closes the circuit of an electromagnet 31, the armature 32 of which is connected by a rod 33 to all of the locking pawl levers 30, whereupon all of the levers 30 are actuated and all of the ratchet wheels 28 returned to a normal or zero position by their springs 29. When in the normal or zero position no lamps of the score indicating device are illuminated, but at each subsequent movement of a ratchet wheel a score indicating lamp is illuminated. This is effected by each set of score indicating lamps, indicated by the reference numeral 36 in Fig. 7 having its individual lamps connected by leads 75

36a to contacts 37 corresponding in number to the number of lamps of the appropriate score indicating set, and each ratchet wheel carrying a corresponding number of radiating contact fingers 40 which are adapted to engage the contacts 37 as the ratchet wheel rotates until ultimately all of the contact fingers 40, thereby all of the lamps 36 of one set, are illuminated. At this stage an audible warning 41 is operated by reason of a supplementary contact strip 42 on each ratchet wheel engaging a supplementary contact 43 connected by a lead 41a to the warning device 41, with which can be combined a visual warning device 44. The circuit is completed by leads 28a to a common battery lead 46 and a common return lead 47. Combined with the circuit embodying the member B¹ is an indicating lamp 41b which is brought into circuit upon completion of the movement of its member 28.

To prevent each throw of a ball from operating effectively more than once against the targets, in order to ensure that only one score for each throw is obtained, a relay electromagnet 48 is energised immediately following the energising of one of the electromagnets B¹, G¹, R¹ or A¹, this being effected by prolonged parts 25a of the armatures 25 engaging and closing contacts 49 adapted to connect a high voltage battery lead 50 to a return lead 51 connected to the electro-magnet 48, the latter being connected in turn to a high voltage battery lead 52. The armature 48a of the electromagnet 48 normally engages and closes a pair of contacts 53 which as shown normally connect the appropriate target contacts 10 to the source of current by the lead 10b and lead 10c. When the electromagnet 48 is energised its armature 48a moves away from and breaks the circuit at the contacts 53, and an extension 48b of this armature engages and closes a pair of normally spaced contacts 54 so that the circuit of the electromagnet 48 is now closed through the contacts 54, a lead 55, a normally closed relay cut-out switch 56 and a lead 57. The relay cut-out switch 56 is located in the runway 15 so that as the ball engages the upper part of the runway 15 it rolls over and depresses the flap 58, thus momentarily deenergising the relay electromagnet 48 and releasing its armature to normal position bringing the target contacts 10 back into circuit and re-establishing normal circuit conditions for the scoring means. The flap 21 when it is moved by a ball closes a switch 59, also preferably a tilting mercury switch, and this switch 59, connects an electromagnet 60, via leads 61 and 62 and junction box J. B. to the high voltage source of current H. V. The armature 60a of this electromagnet carries or itself comprises a stop for the balls, located above a channel 15a in the runway 15, down which channel the balls are guided. This stop is below or in advance of the flap 21, and as the mercury switch 59 is closed by the last ball tilting the board 21, the armature 60a is moved to release the previously played ball. The armature movement is only momentary, so that it returns to normal position to stop the last played ball immediately it has released for further use the previously played ball. The channel 15a communicates at its lower end with a trough 63 to receive the balls for play, and the upper end of this channel is joined to the conveying ends of side guides 64 (see Fig. 2) located beneath the target panel.

In the event of a ball not hitting a target it is necessary to illuminate one of the blue lamps, be-

cause in any event the hitting of a blue lamp target records a "no score" by illuminating a blue lamp. For this purpose the board 21 also carries a switch 70 which is normally open, and is adapted to momentarily bridge the leads 10a and 10b of the blue target contacts 10 and electromagnet B¹, thereby producing the equivalent result of a ball hitting a blue target.

When any one of the ratchet wheels 28 has been moved through a "complete score" angle, i. e., when all six contacts 37 are engaged by the fingers 40, an abutment 71 (carried by each ratchet wheel) engages and opens one of a series of normally closed contacts 71a and thereby breaks the high voltage circuit across the lead 10c and a lead 72.

For the purpose of inspecting the various elements behind the panel 24 a lamp 65 (see Fig. 7) is provided, and the circuit of this lamp is automatically closed by a switch 66 operated by the movement of the cover member or door 24a. A master switch 67 can reset the score indicators to zero without releasing any balls for play, and two pairs of contacts 68, 69 can by hand operation selectively bring into circuit the electromagnet 60 when it is required to release a ball for a trial play. To keep a record of the number of times a complete score is made each rotary member 28 (see Fig. 6) carries an abutment 75 which engages an operating finger 76 of a counting device 77 to obtain a record of the prize scores and the number of coins inserted, thus affording a double check.

I claim:

1. Target game apparatus in which missiles are projected against targets, comprising a plurality of targets, means supporting the targets so that they are individually displaceable when struck by a missile, electrically operated score indicating means, make and break devices operated by movement of the targets to make and break circuits for the score indicating means, a "game-ended" notifying device, means to operate automatically said "game-ended" notifying device and to break the circuits appropriate to the targets when a predetermined number of said targets have been struck, and means automatically breaking the circuit of the operating means of all of the score indicating devices immediately following the displacement of one target by a missile to prevent more than one scoring operation for each discharge of a missile against the targets.

2. Target game apparatus in which missiles are projected against targets, comprising a plurality of targets, means supporting the targets so that they are individually displaceable when struck by a missile, electrically operated score indicating means, make and break devices operated by movement of the targets to make and break circuits for the score indicating means, a "game-ended" notifying device, means to operate automatically said "game-ended" notifying device and to break the circuits appropriate to the targets when a predetermined number of said targets have been struck, means retaining each missile in an inaccessible part of the apparatus after it leaves the targets, and means automatically freeing said missile for replay operated by a subsequently used missile after leaving the targets.

3. Target game apparatus in which missiles are projected against targets, comprising a plurality of targets, means supporting the targets so that they are individually displaceable when struck by a missile, electrically operated score indicating means, make and break devices operated by

movement of the targets to make and break circuits for the score indicating means, said score indicating means comprising a number of indicators, said targets being arranged in a corre-

- 5 corresponding number of sets, means to automatically break the circuits of the targets and score indicators when a complete set of targets has been struck by missiles, and means automatically breaking the circuit of the operating means of all 10 of the score indicating devices immediately following the displacement of one target by a missile to prevent more than one scoring operation for each discharge of a missile against the targets.

4. Target game apparatus in which missiles

- 15 are projected against targets, comprising a plurality of targets, means supporting the targets so that they are individually displaceable when struck by a missile, electrically operated score indicating means, make and break devices operated by movement of the targets to make and break circuits for the score indicating means, said score indicating means comprising a number of indicators, said targets being arranged in a corresponding number of sets, means to automatically break the circuits of the targets and score indicators when a complete set of targets has been struck by missiles, means retaining each missile in an inaccessible part of the apparatus after it leaves the targets, and means automatically freeing said missile for replay operated by a subsequently used missile after leaving the targets.

5. Target game apparatus in which missiles are projected against targets, comprising a plurality

- 35 of targets, means supporting the targets so that they are individually displaceable when struck by a missile, electrically operated score indicating means, make and break devices operated by movement of the targets to make and break circuits for the score indicating means, step by step 40 circuit closing devices to progressively increase the score indications of said score indicating means, coils with armatures and adapted to be energised by the closure of the circuits appropriate to the target operated make and break devices 45 operatively connected to said step by step circuit closing devices, and a relay device automatically breaking the circuit of all of the targets immediately following each energising of the appropriate one of said coils.

50 6. Target game apparatus in which missiles are

- projected against targets, comprising a plurality of targets, means supporting the targets so that they are individually displaceable when struck by a missile, electrically operated score indicating means, make and break devices operated by movement of the targets to make and break circuits for the score indicating means, step by step circuit closing devices to progressively increase the score indications of said score indicating means, coils with armatures and adapted to be energised by the closure of the circuits appropriate to the target operated make and break devices operatively connected to said step by step circuit closing devices, and a relay device automatically breaking the circuit of all of the targets immediately following each energising of the appropriate one of said coils, said relay device comprising an electromagnet or coil with an armature which normally maintains closed the circuit of the target contacts, but when its coil is energised breaks said circuit and closes another circuit to maintain the relay coil energised, said latter circuit including a cut-out device operated to de-energise the relay coil by a missile when returning from the target zone.

7. Target game apparatus in which missiles are projected against targets, comprising a plurality of targets, means supporting the targets so that they are individually displaceable when struck by a missile, electrically operated score indicating means, make and break devices operated by movement of the targets to make and break circuits for the score indicating means, step by step circuit closing devices to progressively increase the score indications of said score indicating means, coils with armatures and adapted to be energised by the closure of the circuits appropriate to the target operated make and break devices operatively connected to said step by step circuit closing devices, and a relay device automatically breaking circuit of all of the targets immediately following each energising of the appropriate one of said coils, said relay device comprising an electromagnet or coil with an armature which normally maintains closed the circuit of the target contacts, but when its coil is energised breaks said circuit and closes another circuit to maintain the relay coil energised, said latter circuit including a cut-out device operated to de-energise the relay coil by a missile when returning from the target zone, an additional circuit closing and breaking means with a circuit closing and breaking means operable by a missile not striking the targets and when returning for replay, and a "no-score" indicator operated from said additional circuit closing and breaking means. 5 10 15 20 25 30

8. Target game apparatus in which missiles are projected against targets, comprising a plurality of targets, means supporting the targets so that they are individually displaceable when struck by a missile, electrically operated score indicating means, make and break devices operated by movement of the targets to make and break circuits for the score indicating means, step by step circuit closing devices to progressively increase the score indications of said score indicating means, coils with armatures and adapted to be energised by the closure of the circuits appropriate to the target operated make and break devices operatively connected to said step by step circuit closing devices, and a relay device automatically breaking the circuit of all of the targets immediately following each energising of the appropriate one of said coils, said relay device comprising an electromagnet or coil with an armature which normally maintains closed the circuit of the target contacts, but when its coil is energised breaks said circuit and closes another circuit to maintain the relay coil energised, said latter circuit including a cut-out device operated to de-energise the relay coil by a missile when returning from the target zone, additional circuit closing and breaking means operating in unison with said relay cut-out device, an electrically energisable device therewith, and an abutment preventing return of each missile to an accessible position for replay operated by said latter electrically energisable device to free the target 35 40 45 50 55 60 65 70 75 80 85 90 95 100

9. Target game apparatus in which missiles are projected against targets, comprising a plurality of targets, means supporting the targets so that they are individually displaceable when struck by a missile, electrically operated score indicating means, make and break devices operated by movement of the targets to make and break circuits for the score indicating means, step by step circuit closing devices to progressively increase the score indications of said score indicating means, coils with armatures and adapted 75

to be energised by the closure of the circuits appropriate to the target operated make and break devices operatively connected to said step by step circuit closing devices, and a relay device automatically breaking the circuit of all of the targets immediately following each energising of the appropriate one of said coils, said relay device comprising an electromagnet or coil with an armature which normally maintains closed the circuit of the target contacts, but when its coil is energised breaks said circuit and closes another circuit to maintain the relay coil energised, said latter circuit including a cut-out device operated to de-energize the relay coil by a missile when returning from the target zone, an additional circuit closing and breaking means with the said cut-out device operable by a missile not striking the targets and when returning for replay, a "no-score" indicator operated from said additional circuit closing and breaking means, a still further circuit closing and breaking means operating in unison with said relay cut-out device, an electrically energised device therewith, and an abutment preventing return of each missile to an accessible portion for replay operated by said latter electrically energisable device to free the ball.

10. Target game apparatus in which missiles are projected against targets, comprising a plurality of targets, means supporting the targets so that they are individually displaceable when struck by a missile, electrically operated score indicating means, make and break devices operated by movement of the targets to make and break circuits for the score indicating means, said score indicating means comprising a number of sets of lamps, a number of step-by-step rotatable circuit closing members for said lamps, a number of electrically energisable devices adapted to impart progressive partial rotary movements to said rotary members, a plurality of contacts movable with the rotary members, a number of fixed contacts engageable by said rotary contacts, each set of lamps being adapted to be illuminated partially or wholly during a complete game, each rotatable member at the completion of a predetermined angle of movement automatically breaking the circuit of the source of supply for the operating means of the score indicating devices when one set of lamps is completely illuminated, and means automatically breaking the circuit of the operating means of all of the score indicating devices immediately following the displacement of one target by a missile to prevent more than one scoring operation for each discharge of a missile against the targets.

11. Target game apparatus in which missiles are projected against targets, comprising a plurality of targets, means supporting the targets so that they are individually displaceable when struck by a missile, electrically operated score indicating means, make and break devices oper-

ated by movement of the targets to make and break circuits for the score indicating means, "no-score" indicating means, a set of targets appropriate to and electrically operatively connected to the "no-score" indicating means, step by step circuit closing devices to progressively increase the score indications of said score indicating means, coils with armatures and adapted to be energised by the closure of the circuits appropriate to the target operated make and break devices operatively connected to said step by step circuit closing devices, and a relay device automatically breaking the circuit of all of the targets immediately following each energising of the appropriate one of said coils.

12. Target game apparatus in which missiles are projected towards targets, comprising a plurality of targets, displaceable members with the targets individually displaceable when struck by a missile, electrically operated score indicating means, make and break devices operated by movement of the displaceable members to make and break circuits for the score indicating means, said score indicating means comprising a number of indicators, said targets being arranged in a corresponding number of sets, means to automatically break the circuits of the displaceable members and score indicators when a complete set of targets has received missiles, means retaining each missile in an inaccessible part of the apparatus after it leaves the targets, and means automatically freeing said missile for replay operated by a subsequently used missile after leaving the targets.

13. Target game apparatus in which missiles are projected towards targets, comprising a plurality of targets, members with the targets displaceable when struck by a missile, electrically operated score indicating means, make and break devices operated by movement of the said displaceable members to make and break circuits for the score indicating means, said score indicating means comprising a number of indicators, said targets being arranged in a corresponding number of sets, means to automatically break the circuits of the said displaceable members and score indicators when a complete set of targets has received missiles, a "game-ended" notifying device, means to operate automatically said "game-ended" notifying device, and to break the circuits appropriate to the displaceable members when a predetermined number of said targets have received missiles, and means automatically breaking the circuit of the operating means of all of the score indicating devices immediately following the displacement of the displaceable member by a missile to prevent more than one scoring operation for each discharge of a missile.

WILLIAM TURRALL. 60
